UNITED STATES PATENT OFFICE.

CARL A. CARLSON, OF ODESSA, MINNESOTA.

DESIGN FOR A PICTURE-FRAME.

40,552.

Specification for Design.

Patented Mar. 1, 1910.

Application filed July 23, 1909. Serial No. 509,234. Term of patent 7 years.

To all whom it may concern:

Be it known that I, CARL A. CARLSON, a citizen of the United States, residing at Odessa, in the county of Bigstone and State of Minnesota, have invented a new, original, and ornamental Design for Picture-Frames, of which the following is a specification, reference being had to the accompanying drawing, forming part thereof.

Figure 1 is a front elevation showing the

design of the picture frame, and Fig. 2 is an edge view thereof.

I claim:

The ornamental design for a picture frame, as shown.

CARL A. CARLSON.
